(57) **CLAIM**

The ornamental design for a beverage sleeve, as shown and described.

DESCRIPTION

FIG. 1 is a top perspective view of a beverage sleeve shown in an environment of use.

FIG. 2 is a top perspective view of the beverage sleeve.

FIG. 3 is a bottom perspective view thereof.

FIG. 4 is a front view thereof.

FIG. 5 is a back view thereof.

FIG. 6 is a right side view thereof.

FIG. 7 is a left side view thereof.

FIG. 8 is a top view thereof.

FIG. 9 is a bottom view thereof; and,

FIG. 10 is a top perspective view of the beverage sleeve of FIG. 1 shown in an alternate configuration in an environment of use.

The broken lines illustrate environment that forms no part of the claimed design.

1 Claim, 10 Drawing Sheets
